(57) **CLAIM**

The ornamental design for an electronic piano, shown and described.

DESCRIPTION

FIG. 1 is a front perspective view of the electronic piano according to the present invention;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

Broken lines in the drawing figures are used to show environmental structure only, and form no part of the claimed design.
